(57) CLAIM

The ornamental design for a shoe, as shown and described.

DESCRIPTION

FIG. 1 is a top, left perspective view of a shoe showing the new design;

FIG. 2 is a left side view thereof;

FIG. 3 is a right side view thereof;

FIG. 4 is a front elevation view thereof;

FIG. 5 is a rear elevation view thereof;

FIG. 6 is a top plan view thereof; and,

FIG. 7 is a bottom plan view thereof.

The broken dashed lines of even length illustrate features of the shoe that form no part of the claimed design. The broken lines of uneven length define portions of the shoe which form no part of the claimed design. The line shading along some surfaces of the shoe, and the stipple shading along other surfaces of the shoe represent a contrast in appearance.
